CLAIM

The ornamental design for a dual tube and closure assembly, as shown and described.

DESCRIPTION

FIG. 1 is a perspective view of a dual tube and closure assembly showing our novel design;

FIG. 2 is a front elevational view;

FIG. 3 is a side elevational view;

FIG. 4 is a fragmentary elevational view of the opposite side;

FIG. 5 is a top plan view;

FIG. 6 is a bottom plan view, FIGS. 1-6 illustrating the dual tube and closure assembly of the invention with the bottoms of the tubes opened for filling;

FIG. 7 is an elevational view similar to FIG. 3 showing the lower ends of the tubes closed;

FIG. 8 is an elevational view similar to FIG. 2 showing the bottoms of the tubes closed;

FIG. 9 is a top plan view of the tube and closure assembly shown in FIG. 7; and,

FIG. 10 is a bottom view of the tube and closure assembly shown in FIG. 8, FIGS. 7-10 illustrating the dual tube and closure assembly of FIGS. 1-6 filled and with the tube bottoms closed.
